UNITED STATES PATENT OFFICE.

ANTHONY COCOZELLA AND ANTHONY COCOZELLA, JR., OF LYNN, MASSACHUSETTS.

FINISHING MACHINE FOR BOOTS AND SHOES.

Application filed April 27, 1925. Serial No. 26,259.

This invention relates to treeing or finishing machines for boots and shoes, and has for one of its objects the production of a machine of this class that is devoid of complexity and unnecessary parts incident to machines heretofore used.

It is a further object of the invention to so construct and arrange a machine of this class that it may be manufactured at very low cost, and of a size enabling it to be secured to a bench or table, and consequently economizing in floor space.

Another object of the invention is to produce a machine of this class that is compact, and fully capable of rendering service equivalent to larger and more complicated and costly machines now in use.

It is also an object of the invention to produce a machine wherein the treeing or finishing of a boot or shoe is accomplished while the boot or shoe is on the making last, thereby obviating the necessity of changing the shoe from the making last to a treeing last of a smaller size and shape, and the liability of the unsatisfactory performance of the finishing operation on a last to which the shoe is not fitted.

A further object of the invention is to so arrange the machine that after the finishing process has been completed, the operator may pull the last from the shoe preparatory to the insertion thereinto of a last suitable for further work to be done.

Other objects of the invention will be fully understood from a description of the drawings and the claims hereinafter given.

Of the drawings:

Figure 1 represents a top plan view of the machine.

Figure 2 is a front elevation of the machine showing a shoe thereon ready to undergo the finishing process.

Figure 3 is a side elevation of the machine with the shoe removed therefrom.

Like characters represent like parts throughout the several figures of the drawings.

Referring to the drawings:

The base 10 has upstanding therefrom the boss 11 into which the spindle 12 is tightly driven or otherwise secured, and which forms a support for the adjustable arms 13 and 14 having the forwardly extending spindles 15 and 16.

The said arms 13 and 14 are slotted as at 17 and 18 and provided with set screws

19 and 20 to tighten the clamp like ends of the arms to the spindle 12; the said spindles 15 and 16 being preferably covered by a resilient material such as rubber tubing 60 to protect the shoe during the finishing operation.

It will be understood that the said arms 13 and 14 are adjustable to accommodate different widths and swing of shoes, and are 65 of such length as to support various sizes of shoes.

Upstanding from the boss 11 is a spindle 21 arranged conveniently for the use of the operator to pull the last from the shoe 70 upon the completion of the finishing operation, which dispenses with the services of a workman for that particular purpose, and occupies but a moment's time of the finishing operator, who must remove the shoe and 75 last from the spindle 12 after finishing the shoe and while they are in his hand the operation of last pulling is rapidly accomplished by a single movement.

From the foregoing it will be readily 80 seen that the present invention contemplates a finishing machine of small compass, capable of rendering service equal to machines of far greater cost and bulk, and combining therewith means to pull lasts from the shoes 85 previously finished on the same machine, thus economizing in first cost, floor space, and dispensing with the services of a workman for pulling the lasts.

Viewing Figure 2 it will be seen that a 90 shoe S, on a last not shown, is in position for the finishing operation to be accomplished on one side thereof, after which the last and shoe will be swung in the direction of the arrow A to occupy the dotted line 95 position at the left of the figure for the finishing operation on the other side.

When both sides have been finished and the shoe otherwise ready to be removed from the machine, the operator will remove 100 the last and shoe from the spindle 12 and engage the socket at the heel portion of the last with the spindle 21, and by one rapid movement pull the last from the shoe and pass both on for further operations.

Having described the invention we claim:

1. A treeing machine of the class described comprising a base portion having a boss upstanding therefrom; a spindle extending from said boss; arms adjustably mounted on said spindle and laterally extending therefrom; and a spindle extending from

each of said arms whereby a last having a shoe thereon may be pivotally supported by said first spindle and laterally supported in turn by each of the other spindles.

5. 2. A treeing machine of the class described comprising a boss having a spindle forwardly extended therefrom; a pair of arms pivotally mounted on said spindle and adjacent said boss, said arms being angularly adjustable rotatively of said spindle; and a spindle extending forwardly from the free end of each of said arms whereby a last having a shoe thereon may be pivotally mounted on said first spindle and laterally supported in turn by each of the other spindles.

3. A treeing machine of the class described comprising a boss; a spindle fast therewith and extending therefrom horizontally and forwardly; and arms laterally extending from said spindle, one each side thereof, and adjustably held thereto by clamp means formed on each arm; a horizontally and forwardly extended spindle at the free end of each arm, said last mentioned spindles each having a resilient cover therefor;

the said first spindle being arranged to pivotally receive a last having a shoe thereon, and said second mentioned spindles being arranged to laterally support a shoe, each in its turn, during the finishing operation 30 thereof.

4. A finishing machine for boots and shoes comprising a base; a spindle arranged to pivotally receive a last having a shoe thereon; and adjustable means arranged laterally 35 with respect to said spindle to support the free end of a last and shoe during certain operations on said shoe.

5. A finishing machine for boots and shoes comprising a base; means to swingingly support a shoe thereon for the purpose of finishing operations; and adjustable means mounted on said base whereby shoes of various sizes and widths may be supported in a manner to aid in said operations. 40

Signed by us at Boston, Massachusetts, this 23rd day of April, 1925.

ANTHONY COCOZELLA.
